[57] CLAIM

The ornamental design for a combined support and carrier for a container or the like, substantially as shown and described.

DESCRIPTION

FIG. 1 is a front elevational view of a combined support and carrier for a container or the like showing our new design;

FIG. 2 is an elevational view looking from the right of FIG. 1;

FIG. 3 is a rear elevational view;

FIG. 4 is a bottom plan view;

FIG. 5 is a top plan view;

FIG. 6 is a perspective view in an operative position;

FIG. 7 is a front elevational view thereof;

FIG. 8 is a side elevational view;

FIG. 9 is a bottom plan view; and

FIG. 10 is a top plan view thereof.

A container and cap are shown in FIG. 7 for illustrative purposes only.
